[57] CLAIM

The ornamental design for a marching shoe heel, as shown and described.

DESCRIPTION

FIG. 1 is a top plan view of a marching shoe heel showing my new design;

FIG. 2 is a rear elevational view thereof;

FIG. 3 is a side elevational view thereof;

FIG. 4 is a front elevational view thereof;

FIG. 5 is a bottom plan view thereof;

FIG. 6 is a side elevational view of an alternative embodiment of a marching shoe heel showing my new design;

FIG. 7 is a bottom plan view thereof; and,

FIG. 8 is a rear elevational view thereof.
